PATENTED AUG. 8, 1905.

B. WOLHAUPTER.
RAIL JOINT.
APPLICATION FILED MAR. 6, 1905.

UNITED STATES PATENT OFFICE.

BENJAMIN WOLHAUPTER, OF CHICAGO, ILLINOIS.

RAIL-JOINT.

No. 796,689.

Specification of Letters Patent.

Patented Aug. 8, 1905.

Application filed March 6, 1905. Serial No. 248,670.

To all whom it may concern:

Be it known that I, BENJAMIN WOLHAUPTER, a citizen of the United States, and a resident of Chicago, in the county of Cook and State of Illinois, have invented certain new and useful Improvements in Rail-Joints; and I do hereby declare that the following is a full, clear, and exact description thereof, reference being had to the accompanying drawings, and to the letters of reference marked thereon, which form a part of this specification.

This invention relates to improvements in rail-joints of that class in which the joint embraces a base-plate on which the ends of the rails rest, provided at one of its side margins with a vertical stiffening-flange, and two joint-bars which are clamped against the opposite sides of the meeting ends of the rails and in which the stiffening-flange on the base-plate is provided with a downwardly-facing shoulder which is engaged with an upwardly-facing shoulder on the adjacent angle-bar to hold the ends of the rails in contact with the base-plate.

The invention consists in the matters hereinafter described, and pointed out in the appended claims.

As shown in the accompanying drawings, Figure 1 is a plan view of a rail-joint embodying my invention. Fig. 2 is a side view thereof. Fig. 3 is a detail section taken upon line 3 3 of Fig. 2. Fig. 4 is a detail section taken upon line 4 4 of Fig. 2.

As shown in said drawings, A A indicate the meeting ends of the rails, B a horizontal base-plate on which the said meeting ends of the rails rest and which is provided at the outer sides of the rails with a vertical stiffening-flange B', and C C' are joint-bars which are fitted between the under faces of the rail-head and the top surfaces of the base-flanges of the rail and are clamped against opposite sides of the rails by means of track-bolts D D. Said joint-bars, as illustrated and preferably constructed, have the form of angle-bars, being provided at their lower margins with stiffening-flanges which extend outwardly over the base-flanges of the rails. The joint-bar C is located at the inner face of the rail, and the joint-bar C' is located at the outer face of the rail, or that adjacent to the flange B' on the base-plate. Said joint-bar C' is provided with an upwardly-facing longitudinal bearing face or shoulder c and the stiffening-flange B' with a downwardly-facing longitudinal

surface or shoulder b, said shoulders c and b being adapted for contact with each other, so as to hold or confine the rails in close contact with the base-plate B. Said upwardly-facing shoulder c on the bar C' is conveniently formed on a longitudinal flange or rib c', extending outwardly from the said bar near the upper margin of the same, and the shoulder b on the stiffening-flange is conveniently formed on an inwardly-directed flange b' at the upper margin of said stiffening-flange. The lower inner face or surface of the said stiffening-flange B', at the base thereof, forms a longitudinal shoulder for contact with the outer margins of the base-flange of the rails, which latter are arranged in contact with said inner surface of the stiffening-flange. The base-plate B is provided in its end portions near its side margins, which project from the inner sides of the rail-flanges, with spike-holes adapted to receive spokes E E, which are driven into the ties F F through said spike-holes. Said base-plate is extended outwardly from the stiffening-flange B' to form a horizontal flange B'', provided near its ends with spike-holes to receive holding-spikes E' E'.

By the construction described the base-plate itself is held by the spikes E and E' from shifting or moving outwardly on the ties under the outward pressure coming on the rails, while the outward shifting of the ends of the rails on the base-plate is prevented by contact of the outer margins of their base-flanges with the longitudinal shoulder formed at the base of the stiffening-flange B'.

The track-bolts E are inserted through and engage the web and joint-bars C C' only and have no connection with the base-plate or its stiffening-flange B'. The result of this construction is that the tightening of the joint by the turning of the nuts on the track-bolts to draw the two joint-bars inwardly has no tendency to shift the rails laterally or to change the lateral position or alinement of the inner edges of the rail-heads, it being manifest that in this construction the lateral position of the rails is positively determined and the rails are always maintained in one position by contact of the outer margins of their base-flanges with the shoulder formed on the base-plate at the base of the stiffening-flange B' and by the immovable attachment of the base-plate by the spikes to the ties.

In order that the longitudinal contact-faces b and c of the stiffening-flange and the

outer joint-bar C' may be maintained in engagement notwithstanding the drawing inward or inward shifting of said angle-bar C' toward the rail-web when the track-bolts are tightened, said contact-surfaces *b c* are arranged at an inclination from the horizontal not greater than that of the top surface of the base-flange of the rail. As a result of this construction when the bar C' is shifted inwardly through the tightening of the track-bolts it rises upwardly on the base-flange of the rail and its upwardly-facing surface *c* is thus retained in contact with the opposed surface of the stiffening-flange. Moreover, when the inclination of the said contact-surfaces *b c* to the horizontal is less than that of the top of the base-flange, as shown in the drawings, such drawing inward of the said bar C' serves to bring said contact-surfaces more closely together, thereby forcing the bar C' against the base-flange of the rail and the latter against the top surface of the base-plate below it and clamping the rail firmly against the said base-plate.

In order to afford an interlocking connection of the outer joint-bar C' with the base-plate in a manner to prevent relative endwise movement of the said parts, the inwardly-extending flange *b'* of the stiffening-flange B' is provided at its ends with prongs *b²*, formed by cutting or slitting said flange *b'* laterally at a short distance inwardly from its ends and by bending said prongs *b²* downwardly into a position to engage the end surfaces of the outwardly-extending flange *c'* on the said bar.

To provide interlocking connection of the inner joint-bar C with the base-plate in a manner to hold said bar from endwise movement relatively to the base-plate, the outwardly-extending flange C² of said bar C is extended outwardly past the base-flange of the rail on which it rests and is bent or directed downwardly at its outer margin, and the central part of said flange C² is cut away so as to form an elongated lateral notch and inwardly-facing transverse bearing-shoulders *c² c²* at the ends of said notch. In connection with such notched construction in the flange of the bar C the adjacent side margin of the base-plate B is provided at its central part with an upwardly-extending or vertical flange B³, equal in length to the distance between the shoulders *c² c²* on the angle-bar C, and which rests within the said notch with its end surfaces in contact with said shoulders. The flange B³ is conveniently formed by cutting or slitting the side margin of the base-plate B transversely and bending up the metal between the cuts or slots therein, the end portions of the inner margin of the base-plate containing the spike-holes for the spikes E E being left flat. The stiffening-flange B' of the base-plate is preferably provided with holes *b³* opposite the track-bolts

D D to facilitate the introduction into place of said bolts after the parts are assembled. The said holes for the spikes E E are located in position with respect to the side margins of the base-plate and to the adjacent side margins of the base-flanges of the rails that the spikes when driven will bear against the outer margins of the spike-holes to hold the base-plate from shifting outward and will at this same time bear against the said base-flanges, so as to force the opposite margins of the base-flange firmly or closely into contact with the base of the stiffening-flange B'. The upturned central flange B³ is preferably arranged at a distance from the stiffening-flange B' slightly greater than the width of the bases of the rails, so that ample space will be afforded between said flanges for the seating of the rail ends on the base-plate in assembling the parts. The downturned margin part of the flange C² on the inner joint-bar C is also preferably extended somewhat outside of the base-flanges of the rails, so as to permit inward movement of the said bar in the tightening of the joint.

A principal feature of my invention is embraced in the construction by which the rail-bases bear laterally against a longitudinal shoulder on the base-plate and the angle-bars are clamped to the rails by bolts which are unconnected with the said base-plate, whereby tightening of the joint-bars against the rails is permitted without any shifting of the rails on the base-plate, and consequently without laterally shifting the rails or changing the gage of the track. Another principal feature of my invention is the provision of opposed contacting surfaces on the stiffening-flange and the adjacent joint-plate, which surfaces are arranged at an angle to the horizontal not greater than that of the tops of the base-flanges of the rails, whereby the drawing inward of said joint-plate on the rails in tightening the joint has no tendency to separate said contacting surfaces. An important advantage is also gained by arranging the said contacting surfaces at a less angle to the horizontal than the top surface of the rail-base flanges, for the reason that by the combination the drawing in of the joint-bar results in the tightening of the rail ends against the base-plate.

I claim as my invention—

1. The combination with track-rails, of a horizontal base-plate provided with a longitudinal, upwardly-extending, stiffening-flange, and at the base of said flange with a longitudinal shoulder against which the side margins of the base-flanges of the rails laterally bear, joint-bars, and bolts engaging the said joint-bars and adapted to tighten the same against the rails without affecting the lateral position of the rails on the base-plate.

2. The combination with track-rails, of a horizontal base-plate provided with a longitu-

dinal, upwardly-extending, stiffening-flange, a joint-bar which engages the sides of the rails between the heads and base-flanges thereof, and bolts clamping said joint-bar to the rails, said stiffening-flange having a downwardly-facing contact-surface which engages an upwardly-facing contact-surface on the joint-bar; the contacting surfaces on the stiffening-flange and joint-bar being inclined at less inclination than the top surfaces of the base-flanges of the rails.

3. The combination with track-rails, of a horizontal base-plate provided with a longitudinal, upwardly-extending, stiffening-flange, and at the base of said flange with a longitudinal shoulder against which the side margins of the base-flanges of the rails bear, a joint-bar which engages the side of the rails between the heads and the base-flanges thereof and bolts acting on the joint-bar to clamp the same against the rails, said stiffening-flange having a downwardly-facing contact-surface engaging an upwardly-facing contact-surface on the joint-bar; the contacting surfaces of the stiffening-flange and joint-bar having inclination not greater than the top surface of the base-flanges of the rails.

4. The combination with track-rails, of a horizontal base-plate provided with a longitudinal, upwardly-extending, stiffening-flange, and at the base of said flange with a longitudinal shoulder against which the side margins of the base-flanges of the rails bear, joint-bars which engage the opposite sides of the rails between the heads and the base-flanges thereof and track-bolts acting on the joint-bars to clamp the same against the rails, said stiffening-flange having a downwardly-facing contact-surface engaging an

upwardly-facing contact-surface on the adjacent joint-bar.

5. A rail-joint comprising a horizontal base-plate provided with a longitudinal, upwardly-extending, stiffening-flange provided with an inwardly-extending rib, and a joint-bar provided with an upwardly-facing surface engaging said rib, said rib being transversely severed to form prongs which are bent into position to engage transverse surfaces of the joint-bar.

6. A rail-joint comprising a horizontal base-plate provided at one side thereof with an upwardly-extending, stiffening-flange, and at its opposite side, with an upturned marginal flange terminating at a distance inwardly from the ends of the plate, and joint-bars, one of which is provided with a flange extending at the ends of the bar outwardly past the central part to form transverse shoulders engaging the ends of the upturned marginal flange on the base-plate.

7. A rail-joint comprising a horizontal base-plate provided at one side thereof with an upwardly-extending, stiffening-flange, joint-bars at opposite sides of the rails, and bolts for clamping said joint-bars against the rails, said stiffening-flange being provided with openings opposite the said bolts to permit the insertion into place of said bolts.

In testimony that I claim the foregoing as my invention I affix my signature, in presence of two witnesses, this 24th day of February, A. D. 1905.

BENJAMIN WOLHAUPTER.
